2

dip being spaced apart at least a quarter of the period length. The period length of the magnetic field is so selected with reference to the electron beam velocity that the border of the electron beam presents at least two bulges during a half period of the magnetic field.

5 The amplification system of an electron beam tube according to the invention is freely selectively wide-banded, because for each fed-in frequency the spatially periodic field always appears as "pump" with double pump frequency. Further, since the beam location in the tube is non-critical, the problem of conducting electron beam with a certain diameter as closely as possible past any electrodes, does not exist.

10 The invention will hereafter be explained in detail, with the aid of the drawings, in which:

15 FIG. 1 is a schematic figure illustrating the construction of a tube according to the invention with a portion of the enclosing envelope broken away to show tube details;

20 FIG. 2 is a graph representing the magnetic field course;

25 FIG. 3 is a graph illustrating the field strength course of the magnetostatic pump field;

FIGS. 3, 4 and 5 are related figures respectively directed to the field strength course of the magnetostatic pump field, the nature of the beam border oscillations of a Brillouin beam, and the magnetic means for the generation of the magnetic field $B(z)$;

30 FIG. 6 is a schematic figure illustrating a portion of a practical magnet arrangement, of the type illustrated in FIG. 5;

35 FIG. 7 is a graph illustrating the magnetic field parameter α , the movement of the center of gravity of the beam, and the representation of the nature of the border of such a beam; and

40 FIG. 8 is a graph illustrating the potential travel variation of the electrons of the electro beam in relation to their disposition with respect to the beam axis and the drift tube.

45 Referring to FIG. 1, reference numeral 1 designates an electron beam generating system, the generated electron beam of which is to permeate successively along the discharge path 2, an input coupling part 3, a drift tube 4 and an output coupling (decoupling) part 5, prior to the electron beam striking the collector 6, both the input coupling part 3 and the output coupling part 5 comprising couplers for transverse waves. In the particular embodiment illustrated, the couplers are constructed in the manner of a so-called Cuccia coupler and consist in each case of a rectangular hollow conductor in which an electromagnetic oscillation is excited by means of an electrical alternating field transverse to the electron beam axis. Such rectangular hollow conductor is provided with two tuning slides 7, arranged symmetrically at both sides of the hollow conductor, making it possible to mechanically tune the coupler to the particular signal frequency. Such a tuning can be omitted if, in an advantageous manner, instead of a Cuccia coupler for the respective coupling parts there is utilized one of the known wide-band couplers for transverse waves, for example in the form of a delay line, which conducts a transverse electrical alternating field.

50 As is apparent from FIG. 2, in the respective zones of the coupling parts there is present a magnetic field 8 or 12 with substantially constant field strength, which, with the use of the Cuccia coupler illustrated, is of such a magnitude that the cyclotron frequency is equal to the signal frequency. The magnetic field 8 with a brief increase in its field strength (magnetic transition field 9), merges into the magnetic pump field 10, which extends over the length of the drift tube 4. The pump field 10, according to the invention, is a magnetic field periodically alternating in direction with a field strength course which has a dip in the middle

ABSTRACT OF THE DISCLOSURE

An electron beam tube with transverse wave modulation, in which transverse waves in the electron beam are amplified by a magnetostatic pump field, the pump field being a magnetic field alternating periodically in direction with a field strength course which presents a dip in the middle of each half period of the magnetic field, and in which system the maxima of the field course on both sides of the dip are separated on the respective sides of the dip by at least a quarter of the period length, with the electron beam being focused in the second or higher pass range.

The invention relates to an electron beam tube with transverse wave modulation for the amplification of high frequency signals with an input coupling part, a drift space and an output coupling part, in which the respective input and output coupling parts consist of a coupler for transverse waves, with a magnetic system being provided which generates a magnetostatic pump field over the length of the drift space with successive magnetic means, the field strength of which pump field changes spatially periodically in electron beam direction, while in the zones of the input coupling and output coupling parts there is present a magnetic field having substantially constant field strength.

Electron beam tubes of this type are already known, in which, for the amplification of the transverse waves (cyclotron or synchronous waves) in the electron beam, there is utilized a magnetostatic pump field running parallel to the electron beam axis, and which has a field component spatially periodically changing in electron beam direction. For the generation of the spatial periodicity there is employed a series of successive cylindrical iron disks, which surround the electron path axially symmetrically.

Such an electron beam tube can be conceived as a parametric amplifier in which, in place of a high frequency pump, the spatially periodic magnetic field produces an amplification of the transverse waves. The advantage of such a tube lies in the fact that, as compared to the conventional traveling wave tubes, no delay line is required and no special attenuation. Moreover there is obtained at the output of the tube an electron beam with an essentially constant electron velocity, so that all the electrons can be decelerated at the collector to substantially zero velocity, and thereby attain a high tube efficiency.

The invention has as its problem that of creating an electron beam tube with transverse wave modulation which, while avoiding a high frequency electric pump voltage, can operate with an electron beam of very high perveance. For the solution of this problem it is proposed, according to the invention, that in an electron beam tube of the type previously mentioned, the magnetostatic pump field be a magnetic field, periodically alternating in direction, with a field strength course which always presents a dip in the middle of a half period of the magnetic field, with the maxima of such field course at both sides of the

70

of a half period of the magnetic field 9. The detailed conditions of this dip as well as the manner of operation of the pump field are hereinafter further explained.

It should be noted here, however, that through the pump field 9 at the input coupling part 3 the electron beam, modulated with a transverse wave, for example cyclotron wave, is focussed as a whole and also the transverse wave is amplified in the beam. After leaving the drift tube, the electron beam passes through another transition field 11, from which the pump field 10 merges into the magnetic field 12 of constant field strength. There is associated with the transition field 11 the advantage that an amplified cyclotron wave receives a clear wave form in the electron beam.

The magnetostatic pump field of an electron beam tube according to the invention is represented, with additional details, in FIGS. 3 to 5. FIG. 3 illustrates the course of the magnetic field strength $B(z)$ with respect to the coordinate z (coordinate in longitudinal direction of the beam path). Therebelow, in FIG. 4, there is depicted the nature of the border oscillations of a Brillouin beam 13 conducted in the magnetic field $B(z)$, while FIG. 5 schematically represents the magnetic means for the generation of the magnetic field $B(z)$ of FIG. 3.

It is well known that the movement of an electron beam in the manner of a so-called Brillouin beam in a magnetic field of sine form is described by a Mathieu equation. The solution of this equation divides into so-called stability and instability ranges. In the instability ranges a deflection of the electrons of the electron beam from the axis is exponentially increased, so that transverse waves, for example cyclotron waves, in passage through such a magnetic field are amplified in the instability range. It is necessary, however, that the electron beam in its totality be preserved. The beam itself, which is characterized by the motion of its border electrons, thus should be maintained. This is possible, despite a so-called positional instability of the individual electrons, in an instability range of the solution of a Mathieu equation if the space charge field in the interior of the beam is included. From the Mathieu equations it results that for a consideration of the stability of the whole beam the same differential equation is obtained as for a space-charge-free electron beam with an additional space charge term. From this it follows that ranges must be present in which the electron beam itself is stable, while shifting of the beam electrons from the beam axis, as a consequence, creates an instability of position. A more precise mathematical investigation has now shown that in use of a magnetic field with a sine form course of the magnetic field strength the instability range involved for an amplification of transverse waves is associated with a theoretical beam focussing, which is practically unusable, as the minimal beam radius takes on values close to zero.

However, considerable space charges can be focussed with a relatively small undularity of the border of the electron beam if a magnetic field of the type illustrated in FIG. 3 is employed. While this magnetic field has a field strength alternating periodically in direction, it does not have a sine form course of the magnetic field strength. On the contrary, the field strength course presents in the middle of each half period of the magnetic field, in which L represents the period length, a dip in which the maxima B_m of the magnetic field strength which bound the dip are separated by at least a quarter of the period length L . The electron beam 13 according to FIG. 4 is focussed in this magnetic field in the so-called second pass range, that is, the range in which the number of border oscillations of the electron beam during a half period of the magnetic field amounts to 2. It should be noted that a focussing of the electron beam in a still higher pass range also is possible. (The ordinal number of the pass range is defined as the number of whole beam border oscillations of the electron beam during a half period of the magnetic field). With increasing ordinal number of the pass range the magnetic field maxima on both sides of the dip should be disposed

further and further apart in the course of the original field strength.

For the generation of the magnetic field course described there are expediently used magnetic means according to FIG. 5, which consist of periodically arranged magnetic poles 14 and 15, which alternate in polarity along the electron path. Centered between the respective magnetic poles 14 and 15 is, in each case, a tubular shield 16 of soft magnetic material, which causes the dip in the field strength course $B(z)$.

FIG. 6 illustrates a section from a practical magnetic arrangement of the type disclosed in FIG. 5, and comprises permanent magnets (not illustrated), which are arranged symmetrically about the electron beam axis z . Opposed, like poles of such permanent magnets, should be alternately connected with one another by pole pieces 17 and 18 extending transversely to the electron beam axis. The thickness of the pole pieces 17 and 18, as viewed in electron beam direction, is reduced in the proximity of the beam axis z with respect to the outwardly disposed parts of the pole pieces. Centered between the two pole pieces 17 and 18 is a shielding cylinder 19, disposed at the height of the rectangular offsets 20 and 21 on the pole shoes 17 and 18. With the dimensional proportions illustrated of the pole shoes 17 and 18, as well as of the shielding cylinder 19, there results the course, represented in broken lines in FIG. 6, of the magnetic field strength over a half period of the pump field in an electron beam tube according to the invention.

The results of a calculation for a magnetic pump field whose magnetic field strength course is described by the function

$$f(z) = \sin \frac{2\alpha z}{L} + 0.5 \sin \frac{6\alpha z}{L}$$

are represented in the diagram of FIG. 7, and, in particular, for a certain so-called magnetic field parameter of the value 3.8. The parameter is determined there from the relation

$$\alpha = \frac{1}{16} \cdot \frac{\eta}{(2\pi)} \cdot 2 \cdot \frac{B_o^3 L_m^2}{U_o}$$

in which $B = B_o f(z)$, L_m is the magnetic period and U_o the electric potential on the electron beam axis. Below the course of the magnetic field $B(z)/B_o$, there is represented in FIG. 7 the movement of the center of gravity of the beam (curve 22), in which there is seen only the projection upon a plane which turns about the beam axis with the rotation of the electrons. Curve 22 is devised from the fact that in the calculation the individual electrons are considered—that is, the Mathieu equation is solved without the inclusion of a member representing the space charge (thread beam free of space charge). Corresponding to this curve, a transverse wave is amplified in the electron beam. However, there is obtained for the whole electron beam, with account taken of the space charge, a beam border corresponding to curve 23 of FIG. 7, the electron beam is accordingly conducted in bundled form in the magnetic field $B(z)$. The calculation further shows that considerable space charge can be focussed, and simultaneously an amplification of a transverse wave is achievable in the electron beam of about 10 to 20 db per magnetic field period.

An electron beam tube according to the invention exhibits like the already known electron beam tubes with transverse wave modulation, the phenomenon that the electron beam velocity diminishes in the direction of the discharge path when the electrons, in consequence of the amplification effect, leave the beam and cross at an angle which becomes greater over the length of the drift space. The electrons then have maximal velocity on the path inclined to the beam axis, so that their velocity, in the direction of the discharge path, is slower. This has the consequence of creating saturation manifestations or nonlinearities. It is possible, however, to eliminate this draw-

back if the variation in travel potential of the electron beam is utilized in order to reaccelerate the electrons in the drift tube. By travel potential there is meant the fact that the electrons have on the axis of the electron beam a potential which is lower than at the beam border, while, in turn, the potential at the beam border is less than the potential of the drift tube surrounding the drift space. For the better understanding of this the travel potential mentioned is represented in FIG. 8, in which the axis of the electron beam is designated by z , the beam border by r and the drift tube by R . For a beam of, for example, 6 a. and 10 kv., which corresponds to a perveance $P=6.10^{-6}$, there results according to the formula

$$\Delta U = U_R - U_o = 1.52 \cdot 20^4 I \cdot U^{-1/2} \left(1 + 4.64 \lg \frac{R}{r} \right)$$

an interior travel potential in the electron beam of

$$\Delta U = 910 \text{ v.}$$

(in the formula U_R represents the voltage on the drift tube, U_o the potential on the beam axis, R the radius of the drift tube and r the beam radius). For a ratio of $R/r=5$ there result for the outer a potential of 3160 v. This outer travel potential between the beam border and the drift tube results in the electron beam being cor- moves far away from its axis. It is now possible to so select the perveance, the beam diameter and the drift tube diameter that in the event of a deflection of the electrons from the beam axis the effective velocity of the electron beam remains constant and, under these conditions, the tube operates linearly. This is always the case when the desired travel potential, in deflection of the electron beam from the axis of the drift tube, satisfies the formula

$$U = U_o \left[1 + \left(\frac{4\pi}{L} \right)^2 \rho^2 \right]$$

in which L designates the period length of the magnetic field and ρ the radius vector in the drift tube.

Changes may be within the scope and spirit of the appended claims which define what is believed to be new and desired to have protected by Letters Patent.

We claim:

1. In an electron beam tube with transverse wave modulation for the amplification of high frequency signals, the combination of an input coupling part, a drift space and a decoupling part, the input coupling and decoupling parts comprising a coupler for transverse waves, a magnetic arrangement which generates over the length of the drift space, with successive magnetic means, a magnetostatic pump field, the field strength of which changes spatially periodically in electron beam direction, while in the vicinity of the input coupling and decoupling parts a magnetic field with essentially constant field strength is present, said magnetostatic pump field being a magnetic field alternating periodically in direction, with a field strength course which always shows a dip in the middle of a half period of the magnetic field, the maxima of the field course on both sides of the dip being spaced apart at least a quarter of the period length, and the period

length of the magnetic field being such in relation to the electron beam velocity that the border of the electron beam presents at least two bulges during a half period of the magnetic field.

5 2. An electron beam tube according to claim 1, wherein in the drift space of the tube is surrounded by a metallic, non-magnetic drift tube.

10 3. An electron beam tube according to claim 2, wherein in the drift tube is charged with such a direct voltage U and its radius R is such that the relation

$$U = U_o \left[1 + \left(\frac{4\pi}{L} \right)^2 \rho^2 \right]$$

15 is fulfilled, in which U_o is the potential on the electron beam axis and L the period length of the magnetostatic pump field.

20 4. An electron beam tube according to claim 1, wherein in the magnetic arrangement for the generation of the pump field consists of permanent magnets which are symmetrically so arranged about the electron beam axis, and are so connected with pole pieces disposed transversely to the electron beam axis, that successively following pole pieces are always oppositely polarized, there being provided, in each case, in the middle between successive pole pieces a soft magnetic hollow shielding cylinder surrounding the electron axis.

25 5. An electron beam tube according to claim 4, wherein in the pole pieces as viewed in electron beam direction, are provided with rectangular offsets, reducing the size of the pieces in the electron beam axis with respect to the outwardly disposed parts of the pole pieces, and the shielding cylinder is arranged at the level of the corresponding rectangular offsets on the pole pieces.

30 6. An electron beam tube according to claim 1, wherein in the magnetic field in the vicinity of the input coupling part and the decoupling part merges in each case into the magnetostatic pump field with a brief elevation of its field strength.

35 7. An electron beam tube according to claim 6, wherein in the input coupling part and decoupling part each consist of a tunable rectangular hollow conductor, in which an electromagnetic oscillation is excited with an electric alternating field transverse to the electron beam axis.

40 8. An electron beam tube according to claim 7, wherein in the rectangular hollow conductor is provided with two tuning slides arranged symmetrically to the electron beam axis.

45 9. An electron beam tube according to claim 6, wherein in the input coupling part and the decoupling part each consist of at least one delay line on which an electromagnetic wave progresses with electric field components directed transversely to the electron beam axis.
